(57) CLAIM

We claim the ornamental design for an accessory for hair styling and hair care apparatus, as shown and described.

DESCRIPTION

FIG. 1 is a bottom perspective view of an accessory for hair styling and hair care apparatus showing our new design;

FIG. 2 is a top perspective view thereof;

FIG. 3 is a side view thereof;

FIG. 4 is a top view thereof;

FIG. 5 is a bottom view thereof;

FIG. 6 is a front view thereof; and,

FIG. 7 is a rear view thereof.

The view opposite the side view of FIG. 3 is a mirror image thereof and, therefore, is omitted.

The broken lines in the drawings depict portions of the accessory for hair styling and hair care apparatus that form no part of the claimed design.
